UNITED STATES PATENT OFFICE.

HOWARD K. KING, OF PHILADELPHIA, PENNSYLVANIA, ASSIGNOR TO CHAMBERS BROTHERS COMPANY, A CORPORATION OF PENNSYLVANIA.

SLIP-SHEETING MACHINE.

1,094,908.

Specification of Letters Patent. Patented Apr. 28, 1914.

Application filed December 14, 1911. Serial No. 685,725.

To all whom it may concern:

Be it known that I, HOWARD K. KING, a citizen of the United States, residing at Philadelphia, in the county of Philadelphia, 5 State of Pennsylvania, have invented a new and useful Slip-Sheeting Machine, of which the following is a specification.

My invention relates to improvements in means for separating slip sheets from between printed sheets.

The object of the invention is to provide improved means for automatically separating and delivering into different piles the printed sheets and intervening slip sheets.

As is well known, the practice in connection with color printing, especially by magazine publishers, is to interpose a blank slip sheet between the printed sheets to prevent smearing or transferring of the colors.

Where very large editions are printed the separation and removal of the slip sheets from the printed sheets, before the latter are folded and bound, becomes quite a serious problem and the object of the present invention is to provide means for automatically accomplishing this work with speed and accuracy.

The invention comprises means whereby the slip sheets are diverted to one pile, while 30 the printed sheets are diverted to another pile, irrespective of the order in which the said sheets are found. That is to say, even in case two slip sheets are found together they still will be diverted to their respective 35 pile.

The invention comprises caliper means, whereby advantage is taken of the difference in thickness between the printed sheet and the slip sheet, so that certain mechanism is 40 set in operation depending entirely upon the thickness of the sheet passing through the caliper device.

The invention comprises switching or diverting means controlled by said mechanism.

The invention also comprises improvements in automatic table actuation.

The invention also comprises automatic switching means, adapted normally to switch to different piles alternate sheets, and manually operative means for arbitrarily reversing the action of the switching means while the machine is operating.

The invention also comprises other de-

tails of construction which will be more specifically described and illustrated.

55

Referring to the drawings, illustrating by way of example, suitable mechanism for effecting my invention Figure 1 is a plan view with tapes, side guides, pushers, chain guards and guide rods removed. Fig. 2 60 is a side elevation of half of the machine. Fig. 3 is a side elevation of the other half of the machine; Figs. 2 and 3 forming a complete side elevation, on a larger scale than Fig. 1. Fig. 4 is a section on line 4—4 65 of Fig. 1. Fig. 5 is a sectional side elevation on line 5—5 of Fig. 1 with parts removed. Fig. 6 is a sectional detail on a vertical plan taken about line 6 of Fig. 3. Fig. 7 is a section on line 7—7 of Fig. 6. 70 Fig. 8 is a section on line 8—8 of Fig. 5. Fig. 9 is a section on line 9—9 of Fig. 1. Fig. 10 is a plan view of the parts shown in Fig. 9. Fig. 11 is a section on line 11—11 of Fig. 9. Fig. 12 is a section on line 12—12 75 of Fig. 9. Fig. 13 is a section on line 13—13 of Fig. 9. Fig. 14 is a detail of the lower nipper shown in Fig. 13 on an enlarged scale and in the open position. Fig. 15 is a section on line 15—15 of Fig. 1. Fig. 80 16 is a plan view of the parts shown in Fig. 15. Fig. 17 is a section on line 17—17 of Fig. 15. Fig. 18 is a section on line 18—18 of Fig. 15. Fig. 19 is a section on line 19—19 of Fig. 15. Fig. 20 is a detail 85 in part section and part elevation showing guide and jogger mechanism. Fig. 21 is a detail showing right hand guide element and means for supporting same. Fig. 22 is a section on line 22—22 of Fig. 1, on an 90 enlarged scale. Fig. 23 is a side elevation of the caliper device showing the air passages in section with the escape nozzle closed. Fig. 24 is a similar view showing the escape nozzle open. Fig. 25 is a rear elevation of the structure shown in Figs. 23 and 24. Fig. 26 is a plan view of same. Fig. 27 is an elevation of the switching device. Fig. 28 is a section on line 28—28 of Fig. 30. Fig. 29 is a fragmentary detail on an 100 enlarged scale in part section and part elevation of mechanism shown in Figs. 27 to 30. Fig. 30 is a section on line 30—30 of Fig. 27. Fig. 31 is a plan view of part of the switching mechanism. Fig. 32 is a perspective detail showing the shaft section 105

taken on line 32—32 of Fig. 31, the view being on an enlarged scale. Fig. 33 is an elevation of the part shown in Fig. 20. Fig. 34 is a plan view of the left hand side jogging mechanism. Fig. 35 is an elevation of the same showing the frame in section. Fig. 36 is a side elevation of the table lowering mechanism. Fig. 37 is a section on line 37—37 of Fig. 36. Fig. 38 is a side elevation of the table raising mechanism. Fig. 39 is a section on line 39—39 of Fig. 38. Fig. 40 is a detail in elevation on an enlarged scale of part of the table operating mechanism. Fig. 41 is a section on line 41—41 of Fig. 40. Fig. 42 is a section on line 42—42 of Fig. 29 on greater enlarged scale.

Similar numerals refer to similar parts throughout the several views.

In describing the present invention it will be understood that the sheets from the pile 60, resting on table 61, see Fig. 2, are fed forward by the combing wheels to the drop and feed rollers 62 and 63 in the usual manner and by mechanism similar to that shown in my Patent No. 789,809, May 16, 1905. The relative position of the drop and feed rollers 62 and 63 with respect to the mechanism of the present invention is shown in Fig. 22.

It will be understood that the pile of sheets resting on table 61 is composed of printed sheets and slip sheets normally alternately arranged. In order that the machine work automatically, irrespective of the arrangement of the slip sheets and the printed sheets, it is necessary that one be thicker than the other.

The present machine embodying my invention has been adapted for operating upon slip sheets which are thicker than the printed sheets. It will of course be understood that by slight changes in the several parts, the device would be equally effective for operating upon slip sheets thinner than the printed sheets. As the sheet reaches the drop and feed rollers 62 and 63, see Fig. 22, it passes between the elements of a caliper device, as indicated in Fig. 22, which controls an air vent from a chamber containing a pneumatic diaphragm, such as is shown in Figs. 27, 28 and 29. This diaphragm controls mechanisms for shifting pins in a rotating element, which we will term a time wheel. These several pins, according to whether or not they are shifted by the diaphragm, either omit to, or actuate a switch which determines the course or direction of travel of each respective sheet which passes through the detector or caliper elements. That is to say, as the sheet passes through the caliper elements and then through the drop and feed rollers 62 and 63, and then through the drop and feed rollers 64 and 65; it travels on

suitable tapes in the usual way between rollers 66 and 67 to the stop 68, whence, according to the position of the switch mechanism, the sheet takes one of two different directions of travel.

Switch mechanism.—This switch mechanism is shown in Figs. 27, 30, 31 and 32, and consists of the member 69 mounted on the rocking shaft 70. The point 71 of member 69 is adapted to project into the annular channel 72 of roller 67. This is shown in Figs. 31 and 32. It is also adapted to rock to the position in which the point stands away from the roller and out of the annular channel, as shown in dotted lines in Fig. 27. It will be obvious that when the point 71 lies within the channel 72 of roller 67 the sheet traveling between rollers 66 and 67 will travel over the top surface 74 of member 69, whereas when the point is raised out of the channel 72 and away from the surface of roller 67, the sheet will be deflected by the arc shaped surface 73 of member 69 and thus carried around the roller 67. When the sheet passes over the incline surface 74 of member 69 it is carried by the rods 75, see Figs. 7 and 22 beneath the tapes 76, to a pair of nippers 77. These nippers 77, there being two pairs, are carried on a pair of chains 79. These nippers are properly actuated to have an open position to receive the sheets, and are then closed upon the sheet to move the sheet forward and then deliver the same to a pile 80, see Fig. 3 as hereinafter to be described. When the sheet passes between the roller 67 and the arc shaped surface 73 of switch 69, it passes between the rods 81 and 82, see Figs. 7 and 22, to the nippers 78, whereby it is carried and delivered to the pile 83, see Fig. 3. When the sheets are delivered alternately to nippers 77 and 78, only alternate pairs of nippers 77 and 78 will receive the sheets, the others moving idly.

Caliper device.—The caliper device is shown in Figs. 23, 24, 25 and 26. Its relative position with respect to other parts is indicated in Figs. 1, 2 and 22. This caliper device comprises a sleeve 84. This sleeve 84 is adjustably secured to the hollow rod 85, which is connected with the stationary framework. This sleeve supports the bifurcated guides 86 between which is trunnioned at 87, the caliper element 88. Integral with caliper element 88 is the upwardly extending arm 89, controlled by the spring 90 and having the surface portion 91 adapted to engage and close the end of nozzle 92. The other caliper element is indicated by 93. By suitable adjustment of the guide 86 which is secured by the graduated nut 94, threaded on the rod 85, the required space between the caliper elements 88 and 93 is secured. The spring 95 is provided within the hollow rod 85 and presses upon the lower part of the sleeve 84 and serves

to take up all play between the adjustable nut 94, the rod 85 and the sleeve 84. The spring 90 normally maintains the part 91 of arm 89 against the end of nozzle 92. It will be noted that the nozzle 92 thereby serves as a stop for the arm 89 and consequently for the caliper element 88. In this position by a suitable adjustment of sleeve 84, a sufficient clearance is left between the caliper elements 88 and 93 for the passage of the thinner of the two sets of sheets, whereas when a thicker sheet, for example a slip sheet, is presented to the caliper elements, there is not sufficient clearance, while said elements are in said normal position, and element 88 is thereupon raised by the thicker sheet. This carries the arm 89 into the position shown in Fig. 24, thereby opening the discharge nozzle 92. The spring 90 is connected at its upper end to the pin 96 which is slidably mounted for the purpose of adjusting the tension of the spring. The spring 90 is connected at its lower end with the arm 89. This spring normally maintains the part 91 of arm 89 against the end of nozzle 92, and hence maintains the caliper element 88 in its lowest position. At the same time, due to the direction of the pull of the spring, it maintains the trunnions against the upper surfaces of their bearings and thus takes up all possible play of the caliper element.

Tail gripper.—As the sheets pass through the drop and feed rollers 64 and 65 they are carried along the tapes 97 beneath the rods 98 toward the drop and feed rollers 66 and 67 and the stop 68. In order however to reduce the speed of travel of the sheets along tapes 97 just prior to their striking the stop 68, I provide the following mechanism. The wheel 99 is provided with a projection 100, see Fig. 22. The wheel 101 is adapted to coöperate with said projection 100. Wheel 101 is preferably mounted on a resilient support and provided with a yielding surface having suitable frictional qualities, such as rubber. The diameter and speed of revolution of wheel 99 is so related that the projection 100 will engage each sheet against the wheel 101, just previous to the front edge of the sheet reaching the stop 68, so as to reduce or check the speed of the traveling sheet just prior to its engagement with said stop 68, in order to prevent injury to the sheet or the violent rebound thereof.

Side guides.—Upon reaching the stop 68, the sheet is engaged between the jaws 102 and 103 of the side guide nipper, shown in Fig. 20, which operates to bring the sheet into proper register against stop 104 in manner similar to that shown in my Patent No. 942,079 dated Dec. 7, 1909. After being brought to proper register, the sheets are then delivered, between rollers 66 and 67,

either to pile 80 or pile 83 as the case may be, as above described.

Pneumatic switch actuation.—As already pointed out, when a thin sheet passes through the caliper device, the elements thereof are unaffected, but when a thicker sheet, such as slip sheet, passes through the caliper device an air nozzle is opened which affects the pneumatic head controlling the switch actuation. The pneumatic head is shown in Fig. 29. This pneumatic head comprises the casing 105 containing a diaphragm 106 which is connected with the piston 107. This diaphragm 106 is subjected to the pressure of an air supply, from any suitable source, such as blower 221, connected through pipe 108, which tends to keep the piston extended into the position shown in solid lines against the tension of springs 109. This piston carries the guide member 110 which is provided with incline surfaces 111 and 112 adapted to coöperate with pin 113 carried by the wheel 114.

The position of the guide member 110 depends upon the pressure in the chamber 115 back of diaphragm 106. This is controlled in the following manner: The feed of air to chamber 115 through pipe 108 is reduced to the very small opening 116 by means of a flattened plug 117 inserted in the restricted channel 118 which communicates with pipe 108. Connected with chamber 115 is also the pipe 119 which terminates in the nozzle 92 as shown in Figs. 23, 24 and 25. When nozzle 92 is closed the pressure of air admitted through aperture 116 is sufficient to actuate diaphragm 106 and piston 107, against the tension of springs 109, to carry the guide 110 into the position shown in solid lines in Fig. 29 and to maintain it in such position. When however, nozzle 92 is opened by the movement of the caliper element and arm 89, as already described, the air will escape from chamber 115 through pipe 119 faster than it can enter through aperture 116, due to the relative capacities of nozzle 92 and aperture 116, with the result that pressure is reduced in chamber 115 and the diaphragm 106 and piston rod 107 yield to the tension of springs 109 to carry the guide member 110 into the position shown in dotted lines in Fig. 29. It will thus be seen that when a thin sheet passes between the caliper elements, nozzle 92 remains closed, and pressure is maintained in 115 sufficient to keep the diaphragm 106 piston 107 and guide 110 in the position shown in solid lines in Fig. 29; in which position each pin 113, which encounters the guide member, is pushed forwardly into a position shown by the upper pin 113 in Fig. 29. In this position, as the wheel 114 slowly rotates, the actuated pin does not encounter the switch arm 120 and hence does not dis-

70

105

110

115

120

125

130

turb the position of the switch 69 as shown in Figs. 27 and 32.

It will be understood that the time wheel and the particular pin actuated is so timed to the position and movement of the particular sheet passing through the calipers, and thereby affecting or not affecting the pin, that the switch will be in the position indicated in advance of the time the sheet reaches a position to be affected by the switch.

When a thick sheet, such as, for example a slip sheet, passes between the caliper elements as already described, the nozzle 92 is opened and air passing from chamber 115 permits the piston 107 and the guide member 110 to respond to the actuation of springs 109, to move into position shown in dotted lines in Fig. 29. In this position the pins 113 are not affected by the guide 110 and will encounter the switch member 120 to actuate the same against the tension of the spring 122, to move the switch member 69 into the position shown in dotted lines in Fig. 27, that is, the point 71 is raised out of channel 71 and away from the surface roller 67. This insures the passage of the slip sheet around the arc shaped surface 73.

It will be understood that each sheet actuates the caliper to control the actuation of a particular pin 113, which controls the actuation of the switch just in advance of the time that that particular sheet reaches the switch. The double incline of guide 110, also of guide 121, is simply to prevent accident in case the machine is turned backward.

Hand operating mechanism.—In case there is not sufficient difference in the thickness of the sheets to cause this automatic detection or caliper which controls the pneumatic shifting of the pins, a hand controlled device may be utilized for securing the switching of alternate sheets to the different piles 80 and 83.

Ordinarily or normally, slip sheets and printed sheets are piled in alternate relation. It happens however that two slip sheets may sometime be together or there may be a failure to feed one or the other of said sheets so that this order of arrangement may be reversed from time to time. To meet this condition the following mechanism is provided: The hub 123 is feathered on the shaft 124 of the time wheel 114 so that said hub will rotate with said time wheel. On this hub are provided the two arms 125 projecting into the same plane, and the arms 126 also projecting into the same plane but in a different plane from that of 125. Arms 125 are provided with pins 127, while arms 126 are provided with pins 128. As shown in Fig. 30 this hub and its several arms are all in the neutral position, that is, in a position that they will not encounter the lever

129 which is also connected with the switch 69 as clearly shown in Fig. 31. The hand lever 130 is pivoted at 131 to the stationary framework and is connected with the hub 123 by a pin projecting in the annular channel 132. By pulling the handle 130 to the left the hub is moved carrying the pins 127 into the operative position so that the arm 129 will be actuated for alternate sheets. As long as this corresponds to the order of the sheets being delivered, they will be properly distributed to the two piles. When however the order changes, the lever can then be moved to the right bringing pins 128 in the operative relationship with lever 129 and the switch is again shifted to change the order of delivery. It will be understood that when the hand operating mechanism is used, the cam or guide 121 is removed, so that the pins 113 may remain in the in-operative position.

Nipper supporting and actuating means.—As all the nippers are alike and are similarly actuated, it will be sufficient to describe one set, such as shown in Figs. 15 and 16, which are carried by the chain 79. The chain 79 is carried by the sprockets 133 and 134. Both of these sprockets are mounted on studs on a common frame, which frame is adjustably mounted on the machine. For example, sprocket 133 is mounted on the stationary stud 135. This stud is mounted on the adjustable frame 136. The sprocket 133 is provided with a hub upon which is mounted the gear 137. Gear 137 is driven by gear 138 feathered on shaft 139. The said gear 138 is kept, in all positions of adjustment, in proper relation with gear 137 by means of the yoke 140 connected with the frame 136 and the channel 141 connected with gear 138. It is obvious of course that shaft 139 is connected with suitable source of power and operated relatively with the other parts of the machine. Sprocket 134 is mounted on stud 142 which is mounted in the slot 143 in the same framework 136 and provided with a tightening bolt 144 for the purpose of taking up wear on the chain or maintaining proper tension thereof. The entire framework 136, carrying both sprocket wheels, is slidably mounted on the rail 145 having a dove tailed engagement therewith. Said frame is further supported on the rail 146, and the adjustable actuation of said frame is secured by means of the adjusting screw 147. All of the nipper sprocket carrying chains are similarly mounted, and adjustable to suit the size of the sheets to be acted upon.

Nipper construction.—As shown in Figs. 10, 13 and 14, the nipper comprises a fixed jaw 148 and a movable jaw 149. The fixed jaw 148 is integral with the channel portion 150, forming a link in the chain as clearly shown in Figs. 10 and 14. The movable

jaw member is secured to the pin 151. To pin 151 is secured one end of spring 152, while the other end is secured to the collar 153, which may be turned for adjusting the tension of the said torsional spring 152. This spring serves normally to maintain the movable jaw 149 in the closed position with respect to the fixed jaw 148. Connected with the movable jaw 149 is the arm 154, carrying the antifriction roller 155. This antifriction roller is adapted to engage, during the travel of the chain around the sprocket wheels, with the stationary cam surface 155, to cause the opening of said nipper to receive the sheet at the beginning of its travel. Upon leaving the surface of said cam the nipper closes, due to the actuation of the torsional spring, as above described, to hold the sheet and carry the same to the delivery position, whereupon the nippers engage the cam surface 156, to cause the opening of the same to release the sheet just prior to its encountering either stop 157 or stop 158, as the case may be, see Figs. 2, 3 and 5.

Guides and joggers.—After the sheets have reached stops 157 or 158, as the case may be, they float down upon their respective piles 80 and 83 between guides 157 and 159 and between guides 158 and 160. Suitable guides such as 161 and 162 are also provided on the sides of the sheet to coöperate in causing the sheet to float down straight onto the pile. Joggers, such as 163 and 164, are provided suitably connected and actuated for jogging the sheets on three sides of the pile to keep the pile true; examples of such actuating means are shown in Fig. 5 and indicated by the cam 165 and cam 166 and the levers and connecting rods shown in association therewith.

An example of a jogger and guide located on the side of the machine from which the sheets are withdrawn, is illustrated in Figs. 20 and 21, also in Fig. 2. 167 indicates the guide and 168 the jogger. These elements are pivotally mounted so that they may be made to withdraw their obstruction from the pile when it is desired to move the pile of sheets from the machine. The guide 167 is pivoted at 169 and is provided with suitable latching means to hold it in either of two positions. The jogger member 168 is pivoted at 170 and is adapted to turn on said pivot to assume the horizontal position above the pile of sheets. In Figs. 34 and 35 is shown another jogger 171 which is slightly different in form and which is used in connection with pile 80. The actuation is similar to the actuation of the jogger shown in Fig. 26.

Table actuating mechanism.—The piles 80 and 83 are delivered to the tables 172 and 173 respectively. These tables are mounted on frames which are supported by the screws 174 and 175, see Figs. 1, 2 and

3. These screws are turned in one direction to elevate the table and in another direction to lower the table.

Lowering actuation.—It is desirable that there may be a lowering actuation to correspond approximately to the feed of the sheets thereto. It is also desirable that there may be an actuation independent of said feed where it is desired to lower the table arbitrarily to the truck or the like. For these different actuations I provide the following means: Referring to Figs. 36, 37, 40 and 41, the driving shaft 176 is provided with a friction wheel 177, provided with a suitable peripheral frictional surface. This wheel 177 coöperates with a friction disk 178 which is mounted on the shaft 179 and is provided with the spring 180 for securing the proper pressure contact between the two frictional elements. The adjustment of spring 180 is secured by the nut 181 on the threaded sleeve 182 which surrounds said shaft 179. Shaft 179 is provided with gear wheel 183 and also with the worm 184. Gear 183 coöperates with the gear 185 mounted on shaft 186 which carries at its other end the beveled gear 187. Worm 184 coöperates with the gear 188 loosely mounted on shaft 189, while gear 187 coöperates with gear 190 also loosely mounted on shaft 189. It will be noted that the gear 190 and gear 188 are driven in the same direction and that the said gears are so proportioned that gear 190 is driven at a much higher speed than gear 188.

Clutch.—Mounted and feathered on shaft 189 between the gear 188 and gear 190 is the clutch element 191 having a double clutch face. One face is adapted to coöperate with the clutch face on 188 and the other is adapted to coöperate with the clutch face on element 190. This clutch element 190 is also connected by a suitable yoke 192 with the actuating lever 193. This hand lever 193 is provided with the spring controlled bolt 194 which is also manually operated by the hand clamp 195 and the bolt is adapted to engage in either of three holes 196, one hole maintaining clutch relations with 188, the other clutch relations with 190, while the middle hole maintains the clutch in the neutral position. It will thus be seen that with the clutch in relationship with 188 the table is fed downwardly in approximate relation with the feed of sheets thereto; while in clutch relation with 190 the table may be lowered arbitrarily at much greater speed. It will be understood that shaft 189 is properly geared by bevels 197 and 198 to shaft 199, see Figs. 36 and 39 and shaft 199 is provided with a gear 200 coöperating with a gear 201 on the screw 174. It will be understood that the pair of screws for each table are driven together.

Adjustment of feed.—In order to secure the required speed to correspond with the

necessary approximateness to the feed of sheets to the table, the friction element 177, see Fig. 36, may be moved along shaft 176 either toward or away from the disk 178. 5 This adjustable movement of element 177 is secured by means of the yoke 202 connected with said element 177, the rod 203 having serrations, and a pinion 204 coöperating with the serrated rod, said pinion being operated by the hand wheel 205. Suitable 10 clamping means are provided to maintain said position of adjustment.

Automatic safety stop.—In order to prevent the downward movement of the table beyond a safe limit I provide the following mechanism: The bell lever 217, see Fig. 37, has one arm adapted to be encountered by the table frame. The other arm is connected by the link 218 to the bell lever 219 which is suitably mounted and has its other arm provided with a yoke 290 engaging in the channel member 220 of rod 179, so that when the table reaches a predetermined point in its descent a part of its framework engages 25 the arm of bell crank 217 which, through the connecting mechanism described, causes the depression of rod 179, against the tension of spring 180, to pull the disk 178 out of operative relationship with wheel 177.

Elevating actuation.—In order to secure the movement of the screws in the reverse direction to cause the elevation of the table I use the following mechanism, see Figs. 38 and 39. On shaft 176 is mounted the pulley 206 which is connected by belt 207 with pulley 208. Pulley 208 is loosely mounted on the shaft 189 and is adapted to coöperate with the clutch element 209 which may be manually operated to bring the pulley into 30 operative relationship with the shaft 189. The tightening pulley 210 is mounted on the lever 211 in such position as to bring the belt 207 under sufficient tension to actuate pulley 208 and shaft 189. It will be understood that the direction of actuation is opposite to that communicated to 189 by the gear referred to and illustrated in Figs. 40 and 41. This is an arbitrary method of elevating the table to bring it into the starting 45 position.

Automatic safety stop.—In order to prevent elevating the table beyond a safe limit, to prevent injury to the machine, a rod 212 is slidably mounted in the framework and 50 provided with a collar 213 at one end, and a collar 214 at the other end. This rod is connected with the rocking lever 215, which in turn is connected with extension 216 of lever 211 by a suitable link, so that when the table reaches an extreme limit of elevation, as shown in dotted lines in Fig. 39, it encounters the upper lug or collar on rod 212, raising the rod and consequently raising the rod end of lever 215 into the position 55 shown in dotted lines. This serves to pull

the lever 211, carrying the tightening pulley 210, into the inoperative position and thus stop further actuation of the table.

Removable tables.—It will be understood that the arrangement of the said tables 172 and 173, and the supporting frame therefor is such that when the truck is run in between the table supporting screws the frame of the table moves down below the top of supporting surface of the truck and delivers the 70 table thereto and permits the truck to carry the table away before the table is raised, one bar of the frame being removable to permit the truck to be withdrawn with the table. This is a well known feature in the art and 75 is therefore neither described nor claimed in this application.

What I claim is:—

1. A machine for automatically separating printed sheets from slip sheets, in accordance with the respective thickness thereof, comprising sheet caliper means actuated by each of one set of sheets only, a switch and means pneumatically operated, controlled by the caliper means, for operating the switch. 85

2. A machine for delivering printed sheets and slip sheets to different points in accordance with the respective thickness of each sheet, which comprises sheet caliper means, a switch and coöperating guides diverging therefrom, and pneumatic means having an air vent controlled by the caliper means, for operating the switch. 95

3. A machine for delivering printed sheets and slip sheets to different points in accordance with the respective thickness of each sheet, which comprises caliper means actuated by each of one set of sheets only, a switch and coöperating guides divergent from said switch, and pneumatic means, controlled by the caliper means, for operating the switch. 100

4. Means for feeding sheets from a common series and means for distributing said sheets alternately to different points, said means including a sheet-controlled switch and arbitrary means for altering the order of such alternate distribution. 110

5. Means for feeding and distributing sheets alternately to different points or piles and manually operative means for arbitrarily changing the order of such alternate distribution while the machine is operating. 115

6. In a machine of the character described, means for distributing sheets in accordance with the respective thickness thereof, comprising a sheet caliper, sheet conveying and guiding means including a switch, and switch operating means including a pneumatic head controlled by the caliper and lever mechanism controlled by the pneumatic head. 120

7. In a machine of the character described, means for distributing sheets in accordance 125

with the respective thickness thereof, comprising a sheet caliper, sheet conveying and guiding means including a switch, and pneumatically actuated switch operating means controlled by the caliper and including a pneumatic head, a time wheel and coöperating switch-controlling lever mechanism.

8. In a slip sheet separating machine, the combination with sheet feeding and distributing mechanism, of means adapted to detect a sheet of predetermined characteristics, and means, including a pneumatic head and coöperating lever mechanism, whereby the operation of certain of the distributing mechanism is controlled.

9. The combination of drop and feed rollers, carrying tapes and guides, a stop adjacent said rollers, means for bringing the sheet into proper register against the stop, a sheet switching or diverting mechanism, adjacent to one of said rollers and coöperating therewith to guide the sheets, sheet caliper means, and switch actuating means controlled by the caliper means.

10. In combination with sheet feeding mechanism, automatically operative sheet controlled sheet switching means, adapted normally to switch to different piles alternate sheets, and manually operative means for arbitrarily reversing the action of the switching means.

11. In combination with sheet feeding mechanism, sheet-controlled sheet switching means, adapted normally to switch to different piles alternate sheets, and manually operative means for arbitrarily reversing the action of the switching means while the machine is operating.

12. A sheet switching mechanism comprising a feed roller, an adjacently disposed deflecting member having a rocking support, adapted in one position to have its point projecting below the periphery of the feed roller, and in its other position its point standing away from the roller, and sheet controlled means for actuating said deflecting member.

13. A sheet switching mechanism comprising a feed roller having a peripheral channel, an adjacently disposed deflecting member having a rocking support, adapted, in one position to have its point projecting into said channel, and another position to have its point withdrawn therefrom, and automatic means controlled by each of one set of sheets only for actuating said deflecting member.

14. A sheet switching mechanism comprising a feed roller, an adjacently disposed deflecting member having a rocking support, adapted in one position to have its point projecting below the periphery of the feed roller, and in its other position its point standing away from the roller, and pneumatically actuated sheet - controlled means for actuating said deflecting member.

15. A sheet switching mechanism comprising a feed roller, a deflecting member having a rocking support, adapted in one position to have its point close to the periphery of the feed roller, and in its other position its point standing away from the roller, and automatic means for actuating said deflecting member, comprising a time wheel, switch actuating pins slidable therein and adapted to project from one side or the other thereof and pneumatically operated means for shifting the pins.

16. A sheet switching mechanism comprising a feed roller, a deflecting member having a rocking support, adapted in one position to have its point close to the periphery of the feed roller, and in its other position its point standing away from the roller, automatic means for actuating said deflecting member, comprising a time wheel, switch actuating pins slidable therein and adapted to project from one side or the other thereof, pneumatically operated means for shifting the pins and a sheet caliper for controlling the pneumatic means.

17. Means for feeding and distributing sheets to different points or piles, comprising a rocking sheet-controlled sheet deflector, coöperating guides and carrying tapes, nippers and means for moving and actuating the same to deliver the sheets to a required point.

18. Means for feeding and distributing sheets to different points or piles, comprising a rocking sheet-controlled sheet deflector, coöperating guides and carrying tapes, a plurality of sets of nippers and means for moving and actuating the same to deliver the sheets to a required point.

19. A sheet switching mechanism and actuating means therefor comprising a rotating element, projecting devices carried thereby, means for shifting the projecting devices with respect to the carrying element, comprising a guide member for engaging the projecting devices, a pneumatic head and diaphragm operating therein, a piston connected with the diaphragm and carrying the guide member, an air supply under pressure, an air inlet and an outlet connected with the head, the outlet normally greater than the inlet, a sheet caliper and means controlled thereby for controlling the air outlet.

20. A sheet switching mechanism and actuating means therefor comprising a rotating element, projecting devices carried thereby, adapted to encounter the switching mechanism when in one position, means for shifting the projecting devices with respect to the carrying element, comprising a guide member for engaging the projecting devices, a pneumatic head and diaphragm operating therein, a piston carrying the guide member, connected with the diaphragm, an

air supply under pressure, an air inlet and an outlet connected with the head, the outlet normally greater than the inlet, a sheet caliper and means controlled thereby for controlling the outlet.

21. A sheet switching mechanism and actuating means therefor comprising a rotating element, projecting devices carried thereby, adapted to encounter the switching mechanism when in one position, means for shifting the projecting devices with respect to the carrying element, comprising a guide member for engaging the projecting devices to render them ineffective, a pneumatic head and diaphragm operating therein, a piston carrying the guide member connected with the diaphragm, an air supply under pressure, an air inlet and an outlet connected with the head, the outlet normally greater than the inlet, a sheet caliper and means controlled thereby for controlling the outlet.

22. A sheet switching mechanism and actuating means therefor, comprising a rotating element, projecting devices carried thereby adapted to encounter the switching mechanism when in one position, automatic means for shifting the projecting devices into the inoperative position.

23. A sheet switching mechanism and actuating means therefor, comprising a rotating element, projecting devices carried thereby adapted to encounter the switching mechanism when in one position, pneumatically operated means for shifting the projecting devices into the inoperative position.

24. A sheet switching mechanism and actuating means therefor, comprising a rotating element, projecting devices carried thereby adapted to encounter the switching mechanism when in one position, pneumatically operated means for shifting the projecting devices into the inoperative position and means for returning the projecting devices to initial or effective position.

25. A sheet switching mechanism and actuating means therefor, comprising a rotating element, projecting devices carried thereby adapted to encounter the switch mechanism when the rotating device is in one position and manually operative means for shifting the position of the rotating device.

26. A sheet switching mechanism and actuating means therefor, comprising a rotating element, projecting devices carried thereby adapted to encounter the switch mechanism when in one position, means for shifting the projecting devices with respect to the rotating carrying device, a second rotating element carrying projecting devices adapted to encounter a switch mechanism when the rotating device is in one position and manually operative means for shifting the position of the rotating device.

27. In a sheet feeding and distributing

machine, a sheet-controlled sheet switching device, feed rollers, carrying tapes and guides, sheet conveying nippers and means for moving and actuating the same to deliver the sheets.

28. In a sheet feeding and distributing machine, a sheet-controlled sheet switching device, feed rollers, carrying tapes and guides, sheet conveying nippers and means for moving and actuating the same, to effect the delivery of the sheets into separate piles.

29. In combination with sheet switching mechanism, feed rollers, carrying tapes, guides and carrying nippers, and carrying chains, each nipper having a fixed jaw and a movable jaw, and a channeled portion connected with the fixed portion and forming an integral part of a link of the carrying chain.

30. In combination with sheet switching mechanism, feed rollers, carrying tapes, guides, carrying nippers, and carrying chains, each nipper having a fixed jaw and a movable jaw, the fixed portion having a channeled portion connected therewith, said channeled portion forming an integral part of a link of the carrying chain, the movable jaw being spring controlled, and provided with a projection, and a fixed incline adapted to encounter the projection during the travel of the chain, to actuate the movable jaw against the spring control.

31. In combination with sheet switching mechanism, feed rollers, carrying tapes and guides, a receiving table, sheet-conveying mechanism between the switching mechanism and the receiving table, a vertical guide and side and end joggers associated therewith.

32. In a slip sheet separating machine, the combination of sheet switching mechanism, feed rollers, carrying tapes and guides, receiving tables and vertical guide and side and end joggers associated therewith, and pivotally mounted so that they may be moved to clear the piles when it is desired to withdraw the tables and piles from the machine.

33. In a slip sheet separating machine, the combination with sheet switching mechanism, of separate receiving tables for the printed sheets and the slip sheets, screws for elevating and lowering said tables, and means for actuating the screws in either direction, said means comprising adjustable friction transmissions whereby the automatic lowering of the tables may be made to correspond approximately with the feed of sheets thereto.

34. In a slip sheet separating machine, the combination with sheet switching mechanism, of separate receiving tables for the printed sheets and the slip sheets, screws for elevating and lowering said tables, means for actuating the screws in either direction.

5 said means comprising adjustable friction transmissions whereby the automatic lowering of the tables may be made to correspond approximately with the feed of sheets thereto and means whereby the lowering actuation of the screws may be made independent of the friction transmissions.

10 35. In a slip sheet separating machine, the combination with sheet switching mechanism, of separate receiving tables for the printed sheets and the slip sheets, screws for elevating and lowering said tables, means for actuating the screws in either direction, said means comprising adjustable friction transmissions whereby the automatic lowering of the tables may be made to correspond approximately with the feed of sheets thereto, and means whereby said lowering actuation of the screws may be arbitrarily 15 made independent of the friction transmissions.

20 36. In a slip sheet separating machine, the combination with sheet switching mechanism, of separate receiving tables for the printed sheets and the slip sheets, screws for elevating and lowering said tables, means for actuating the screws in either direction, said means comprising adjustable friction transmissions whereby the automatic lowering of the tables may be made to correspond approximately with the feed of sheets thereto, and clutch and associated mechanism for varying the speed of actuation of the feed screws.

25 37. In a slip sheet separating machine, the combination with sheet switching mechanism, of separate receiving tables for the printed sheets and the slip sheets, screws for elevating and lowering said tables, means for actuating the screws in either direction, said means comprising adjustable friction transmissions whereby the automatic lowering of the tables may be made to correspond approximately with the feed of sheets thereto, and clutch and associated mechanism for varying the speed of actuation of the feed screws from the friction transmissions through a neutral position of the clutch.

30 38. In a slip sheet separating machine, the combination with sheet switching mechanism, of separate receiving tables for the printed sheets and the slip sheets, screws for elevating and lowering said tables, means for actuating the screws in either direction, said means comprising adjustable friction transmissions whereby the automatic lowering of the tables may be made to correspond approximately with the feed of sheets thereto, and automatic means for making the friction transmissions ineffective when the tables reach predetermined points.

35 39. In a slip sheet separating machine, the combination with sheet switching mechanism, of separate receiving tables for the printed sheets and the slip sheets, screws for

elevating and lowering said tables, means for actuating the screws in either direction, said means comprising adjustable friction transmissions whereby the automatic lowering of the tables may be made to correspond approximately with the feed of sheets thereto, and safety stops comprising projections adapted to be encountered by the tables and connecting mechanisms to cause a separation of the friction elements.

40 70 75 35. In a slip sheet separating machine, the combination with sheet switching mechanism, of separate receiving tables for the printed sheets and the slip sheets, screws for elevating and lowering said tables, means for actuating the screws in either direction, said means comprising adjustable friction transmissions whereby the automatic lowering of the tables may be made to correspond approximately with the feed of sheets thereto, and clutch and connecting mechanism for causing the actuation of the screws in the opposite direction.

45 80 85 90 95 100 41. In a slip sheet separating machine, the combination with sheet switching mechanism, of separate receiving tables for the printed sheets and the slip sheets, elevating screws for said tables, means for actuating said screws comprising driving pulleys, belts and belt tightening pulleys and means for actuating the tightening pulleys, safety stops comprising lugs or projections adapted to be encountered by the tables and connecting mechanisms between the lugs and the tightening pulley actuating means.

50 105 110 115 120 42. In a slip sheet separating machine, the combination with sheet switching mechanism, of separate receiving tables for the printed sheets and the slip sheets, elevating screws for said tables, actuating means therefor, comprising belts, pulleys and belt tightening devices, and safety devices comprising lugs to be encountered by the tables and means for establishing operative relationship between the lugs and the belt tightening devices.

55 43. A slip sheet separating machine, comprising in combination with conveying mechanism for the sets of intermingled printed sheets and slip sheets, a sheet-controlled detector element actuated by each of the sheets of one set only and means controlled thereby, for diverting the sheets of one set from the path of travel of the sheets of another set.

60 125 44. A slip sheet separating machine, comprising in combination with conveying mechanism for the sets of printed sheets and slip sheets, a detector element controlled entirely by the sheets of one of said sets, means controlled thereby for diverting the sheets of one set from the path of travel of the sheets of another set.

65 45. A slip sheet separating machine, comprising in combination with conveying

mechanism for the sets of printed sheets and slip sheets, a detector element and means controlled thereby, including a pneumatic head and coöperating lever and sheet-switching mechanism, for diverting automatically the sheets of one set from the path of travel of the sheets of another set.

46. In a slip sheet separating machine, the combination of conveying mechanism for the separate sets of printed sheets and slip sheets, a detector element adapted to be operated by each sheet of one of said sets of sheets only, and a sheet deflector operatively connected with the detector element.

47. In a slip sheet separating machine, the combination of conveying mechanism for the intermingled printed sheets and slip sheets, a detector element controlled entirely by each sheet of one of said sets of sheets, irrespectively of the order of arrangement, a sheet deflector and means between the detector element and the sheet deflector whereby the actuation of the detector element automatically controls the sheet deflector.

48. Means for separating a plurality of sets of sheets of different characteristics comprised in a common series of sheets movable in a common path of travel comprising means for moving the sheets and sheet-switching means controlled by the sheets of one of said sets only.

49. Means for separating a plurality of sets of sheets comprised in a common series of sheets normally movable in a single common path of travel, comprising means for moving the sheets and sheet-switching means controlled by the sheets of one of said sets only.

50. Slip sheet and printed sheet separating mechanism comprising means for moving the sheets, sheet-controlled sheet-switching-means, adapted normally to switch to different points alternate sheets, and means for arbitrarily changing the action of the switching means.

51. Sheet switching mechanism for separating printed sheets from slip sheets comprising coöperating drop and feed rollers, stops adjacent thereto, and a side guide nipper as means for bringing the sheet into proper register against one of the stops and a movable sheet-controlled deflecting member controlled by the sheets of one set only adapted to control the path of travel of the sheets fed between said rollers.

52. Means for separating and distributing a plurality of sets of sheets of different thicknesses comprised in a common series of sheets movable in a common path of travel, comprising means for moving the sheets and means whereby alternate sheets are normally directed to different points, said means adapted to change automatically said order of distribution.

53. Means for separating and distributing

slip sheets and printed sheets normally alternately arranged in a common series, comprising means for moving the sheets, means for diverting the slip sheets from the path of travel of the printed sheets, said means normally controlled by alternate sheets but adapted to be controlled by successive sheets in the event of a change in the normal arrangement of the series of sheets, and a plurality of separate sets of chains and chain nippers as means for separately delivering the separated sets of sheets.

54. Means for separating and distributing slip sheets and printed sheets normally alternately arranged in a common series, comprising means for moving the sheets, and sheet-controlled means for diverting successively the sheets of one set of sheets from the path of travel of the sheets of the other set of sheets, said sheet-controlled means adapted automatically to change the order of distribution of the slip sheets and the printed sheets in the event of the consecutive arrangement of sheets of one set in said series.

55. A machine for separating printed sheets from slip sheets, comprising a sheet-controlled switch controlled by the sheets of one set only, a receiving table, a stop between the switch and the table, and side registering means for alining the sheets upon the table before they are operated upon by the switch.

56. In an apparatus for separating intermingled printed sheets and slip sheets normally alternating, the combination of means for moving the sheets and means whereby alternate sheets of the series will be separated normally from the other sheets and delivered to a different point, said means adapted to be controlled entirely by each advancing sheet of one set of sheets only to change the order of delivery of the sheets.

57. In an apparatus for separating intermingled printed sheets and slip sheets normally alternating, the combination of means for moving the sheets and means whereby alternate sheets will normally be separated and delivered to a different point, said means adapted to be automatically controlled by the sheets of one set only to change the location of delivery of successive sheets in the event of failure of said normal alternation of arrangement.

58. In an apparatus for separating intermingled printed sheets and slip sheets, means for moving the sheets and automatic means controlled by each of the sheets of one set only for separating the printed sheets and the slip sheets irrespectively of the order of their arrangement.

59. In an apparatus for separating a common series of intermingled printed sheets and slip sheets, the combination of means

for moving the sheets, sheet-controlled means for separating the printed sheets and the slip sheets irrespectively of the order of said sheets in the common series, and means for arbitrarily controlling the operation of the separating means by hand.

60. In an apparatus for separating a common series of intermingled printed sheets and slip sheets, the combination of means for moving the sheets and means including a detector element, a pneumatic diaphragm and a coöperating sheet deflector for separating the printed sheets from the slip sheets irrespectively of the order of said sheets in the common series.

61. In an apparatus for separating a common series of intermingled printed sheets

and slip sheets, the combination of means for moving the sheets, means for separating automatically the printed sheets and the slip sheets irrespectively of the order of said sheets in the common series, means for distributing said separated sheets to different points, means for arbitrarily controlling the sheet separating means to cause the automatic separation of alternate sheets of the common series, and means for controlling the operation of the sheet separating means by hand to cause the distribution of successive sheets to the same point.
